UNITED STATES PATENT OFFICE

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY

BOILER BAFFLE

Application filed July 20, 1922. Serial No. 576,184.

My present invention relates to baffles for steam boilers, particularly for such boilers having horizontally inclined tubes with baffles extending generally in a direction crosswise of the tubes.

My invention will be best understood from the following description and the annexed drawings, in which Fig. 1 is a typical form of steam boiler embodying my invention in one form; Figs. 1^a and 1^b are detail views of the inclined baffle shown in Fig. 1; Fig. 2 is a section on the line 2—2 of Fig. 1; Fig. 3 is an enlarged sectional elevation on the line 3—3 of Fig. 4 of a baffle showing a modification of the construction shown in Fig. 1; Fig. 4 is a front elevation of Fig. 3; Fig. 5 is a side elevation of one of the tiles shown in Figs. 3 and 4; Fig. 6 is an enlarged section on the line 6—6 of Fig. 3; Fig. 7 is an enlarged side view of one of the elements in Fig. 3; Fig. 8 is a view similar to Fig. 3, showing a modification and taken on the line 8—8 of Fig. 9; Fig. 9 is a front view of Fig. 8; Fig. 10 is a section through the baffles shown in Figs. 8 and 9 taken on the line 10—10 of Fig. 8; Figs. 11, 12 and 13 are respectively side, front and plan views of one of the elements shown in Figs. 8 and 9; Fig. 14 is a section on the line 14—14 of Fig. 11; Fig. 15 is a section on the line 15—15 of Fig. 8; Fig. 16 is a view similar to Fig. 15 showing a modification; Fig. 17 shows one of the tile use in Fig. 16, and Fig. 18 shows another of such tile in cross-section.

Like reference characters indicate like parts in the several views.

In Fig. 1 is shown a boiler having horizontally inclined tubes divided into an upper bank 10 and a lower bank 11 spaced apart to form a chamber between the banks, the chamber in this case accommodating a superheater having tubes 12 extending inward from the sides of the setting and connected by headers 13 and 14. Above the upper bank 10 is a superheater having tubes 15 connected by headers 16 and 17. The two superheaters are connected in series, as shown in dotted lines in Fig. 2, with the steam and water drum 18.

Above the lower bank 11 and extending

from the down-take headers thereof is a short baffle 19. From the end of the baffle 19 extends a baffle across the space between the banks and also across the upper bank, the baffle shown in Fig. 1 being made up of a lower and an upper portion, the lower portion, which is the part which extends across the space, being inclined to the horizontal, and the part which extends across the tubes being vertical in the form illustrated.

In Fig. 1, the lower portion of this baffle is made up of metallic members 20 having engaging pieces 200 which in turn engage with the flanges on I-beams 21 extending across the setting and fixed in the side walls. On the front and lower side of the metallic members 20 are bulbed projections on which are suspended tile 22, this connection being similar to any of the forms shown in the remaining figures to be described more fully hereinafter. From the construction illustrated in Fig. 1, it will be seen that the weight of the tile is supported through the metallic pieces 20 by the beams 21 with the tile between the metallic parts to protect them from the hot gases flowing upward across the lower bank 11 into the superheater chamber. At the same time, by inclining the baffle across this space, the pass for the gases through the chamber is gradually decreased to maintain the velocity of the gases as they are cooled by contact with the superheater tubes.

The baffle across the upper bank 10 will be made up preferably in the usual manner with metallic plates and a refractory material in front of such plates, these metallic plates being anchored to the tubes of the bank 10. The upper part of the lower portion of the baffle contacts with the lower part of the baffle across the upper bank 10 so as to assist in taking up the overturning moment of the lower portion of the baffle.

Referring now to the arrangement shown in Figs. 3 to 7, inclusive, the upper and lower portions of the baffle in the arrangement here shown are in the same plane; that is to say, the inclined baffle across the space between the banks is continued in the same direction across the tubes of the upper bank instead of being formed in two planes as shown in Fig.

1. The baffle across the upper bank is made up of a series of backing plates 23 fitting around the tubes and overlapping, as shown in Fig. 3, to form a substantially gas-tight joint. Two rows of tile 24 extend in front of these plates and are supported on the tubes 10. Cross bars 25 may be located in the diagonal aisles of the tubes in contact with the rear faces of the plates 23; these bars being held in place by members 26 between the bars and clamps 27 connected to the tubes 10.

The lower portion of the baffle extending across the space between the banks, in the form shown in Figs. 3 to 7, inclusive, has a plurality of metallic plates 28 placed side by side across the boiler, these plates extending the entire distance between the two banks and, in the form shown, having a foot portion 29 extending parallel to the baffle 19 and engaging an upstanding projection in that baffle. At the upper portion of the plates 28, there is a tongue-like portion which engages back of a similar tongue-like portion of the lower edge of the lowermost plate 23 of the upper portion of the baffle, and preferably the plates 28 and this lowermost plate 23 are connected by straps 30 bolted to the two plates. Preferably, the lower portion of each of the diagonal bars 25 is notched, as at 31, and flat bars 32 are passed through these notches and extend back of the plates 28.

In the form shown, the plates 28 have projections 33 on their front faces, these projections, in the illustrative form, being provided with bulbs, the projections and the bulbs extending vertically along the faces of the plates 28. Tile 34 are threaded on the projections 33 and in the manner best shown in Fig. 6, each of the tile having a recess on its side which cooperates with a recess on the adjacent side of the next row of tile to form a recess which will engage around the bulb of the projection 33. Preferably, the projections 33 stop short of the bottoms of the plates 28 so as to leave sufficient distance to permit a tile to be inserted at the bottom of the plate 28 and moved upward into position on the projections 33. Fig. 5 shows one of the tile 34 and the arrow indicates the direction in which it is moved to bring it in position to be moved upward into place. After all of the tile except the last one have been positioned, the last tile can be moved into place to support the tile above it, this tile being held by the weight of the row of tile which it supports.

Preferably, the side faces of the tile 34 are arranged so that the joint at the front of these tile is out of alinement with the projections 33, the side faces being curved in Fig. 6 to accomplish this. Between the tile 34 and the plates 28 may be a layer of insulating material 35. Preferably, the joints between the plates 28 are arranged so that no parallel joint in the tile 34 comes opposite such joint

between the plates. By forming the recesses for the bulb projections and the associated joints between the tiles so that the outer portion of each joint is out of alinement with each projection, the tiles form a screen for the radiant heat, and no straight path for the radiant heat to the bulb projections is produced, thereby protecting the bulb projections which are usually formed of cast iron from intense heat. The joint between adjacent tiles is formed of three portions, the front and rear portions being at right angles to the faces of the tiles, the rear portion coming opposite the bulbed projection and the front portion being offset therefrom. The two portions are joined by a third portion in which the change of direction is gradual. By forming the tiles in this manner, there are no projecting tongues or any sharp projecting corners which are in practice easily broken, and the strength of one tile is not sacrificed in favor of an adjacent tile. It will, of course, be understood that with the water tubes spaced in the described manner, the tiles in the inclined baffle are subjected to the radiant heat of the furnace which can pass through the diagonal lanes between the tubes of the lower bank. Furthermore, the tiles are subjected to radiant heat from any flames in the superheater chamber.

In the arrangement shown, the plates 28 are held securely in position, the tendency to slide down the tubes being taken up by the bars 25 through the clips 27. The bars 32 extending to the bottom of the plates 28 transmit some of this pressure to the diagonal bars 25. Furthermore, the projection 29 further assists in transmitting some of the weight of the baffle to the baffle 19 and thence to the uptake headers. By reason of the connection between the upper part of the plates 28 and the main baffle extending across the upper tubes, the tendency of the inclined baffle across the space to overturn or fall to the right of Fig. 3 is taken up.

The tile 34 are partly suspended on the plates 28, and there is sufficient freedom in the recesses surrounding the projections 33 to permit a certain amount of lateral movement which might be induced by changes in the heat conditions of the furnace. The straps 30 also transmit some of the weight of the lower portion of the baffle to the upper portion and from thence to the upper bank of tubes. By forming the side faces of the tile so that the joint at the front is out of alinement with the projections 33, no radiant heat can strike the projections through the spaces that are left between the tiles, as illustrated, to allow for expansion, and the possibility of the hot gases striking such projections is minimized. It is advantageous to form the side faces of the tiles so that the joints at the front faces of the tiles which come in contact with the hot gases are out

of alignment with the corresponding joints on the opposite side of the tiles, which causes them to be out of alignment with the bulb projections 33, as by so doing the side faces 5 may be curved to a larger radius than should a tongue and groove construction be employed at the sides of the tiles. Through using the construction described the tiles are formed in such a way that there are no sudden changes in the contour and may be made 10 of a shape that can be burned in their manufacture to a more uniform grade than when there are sudden changes of form in the contour. Tiles made in this way will stand up better in service than those having sudden changes in the form of the contour.

The arrangement shown in Figs. 8 to 15, inclusive, is similar to that just described, except that, instead of the plates 28, the rear portion of the baffle across the space may be made up of a heat-resisting material, which, if desired, may be formed up as a wall of tile or the like or as a continuous hardened plastic. Such an arrangement is shown at 36. 20 The diagonal bars 25 are provided at their lower portions with holes through which extends a bar 37 on which, in turn, are threaded metallic members 38 having a bulbed portion 39 and an engaging end 40, the web of the member 38 extending through the backing 25 36 with the bulbed portions 39 in front thereof. On these bulbed portions are suspended tile 410 having recesses in their sides in the manner similar to that shown in Fig. 6 to 25 surround the bulbs 39, so that the tile is supported on the metallic members 38, which, in turn, are engaged by the rod 37 projecting through the lowermost portion of the diagonal bars 25. The ends 40 of the metallic 30 members 38 engage the lowermost one of the backing plates 23 of the baffle extending to the upper bank of tubes. The tendency for the baffle across the space to slide downward is taken up by the diagonal bars 25 and is also resisted by the contact between the lower left-hand side of the members 38 with the upper end of the baffle 19. The tendency of this portion of the baffle to overturn is prevented by the extension 40 engaging the plates 23 and 35 some of the weight of the lower portion of the baffle is transmitted to the upper tubes of the tile 410 connecting the metallic members 38 with the plates 23. In this arrangement, the bulb portion 39 is as long as the metallic 40 members 38, the special tile 42 being removed while the tile 41 are being moved into position on the bulb 39 and then the tile 42 is inserted, this latter tile supporting the weight of the tile 41 above it.

In Figs. 16, 17 and 18 is shown a further modification in which the metallic pieces 43 45 are similar to the pieces 38, but are L-shaped in cross-section, the hooks on the pieces 43 extending alternately in opposite directions to engage grooves 44 in the main tile 45. Aux-

iliary tile 46 are moved into position between the members 43 after these latter have been moved laterally so that their hooks engage in the grooves 44 of the tile 45.

It will be understood that my invention 70 may be varied within wide limits and that the arrangements shown are merely illustrative.

I claim:

1. A water tube boiler having banks of 75 tubes with a space therebetween, and a baffle extending within the space and inclined to the vertical, said baffle comprising fixed metallic members and tile attached to and at least partly supported by said fixed members 80 and located on the lower side of the baffle.

2. In a steam boiler having horizontally inclined tubes divided into banks with a space therebetween, a baffle extending across the space and inclined to the vertical, said baffle 85 comprising fixed metallic members and tile attached to and at least partly supported by said fixed members and located on the lower side of the baffle.

3. In a steam boiler having horizontally 90 inclined tubes divided into banks with a space therebetween, a baffle extending across the space and inclined to the vertical, said baffle comprising fixed metallic members having headed projections on their lower side, 95 and tile attached to said projections and located on the lower side of the baffle.

4. In a steam boiler having horizontally inclined tubes divided into banks with a space 100 therebetween, a baffle extending across the space and inclined to the vertical, said baffle comprising fixed metallic members having vertically extending bulbed projections on their lower side and tile having recesses engaging said bulbed projections and suspended 105 on the lower side of the baffle.

5. In a steam boiler having horizontally inclined tubes divided into banks with a space therebetween, a baffle extending across the space and inclined to the vertical, said baffle 110 comprising metallic plates extending from the lower to the upper bank and located side by side across the space, said plates having projections on their front and lower faces, means to anchor said plates to prevent their overturning, and tile attached to the said projections and suspended on the lower faces 115 of said plates.

6. In a steam boiler having horizontally inclined tubes divided into banks with a space therebetween, a baffle extending across the space and inclined to the vertical, said baffle comprising metallic plates extending from the lower to the upper bank and located side by side across the space, said plates having vertical bulbed projections on their front and lower faces and tile having recesses engaging said bulbed projections and suspended 120 on the lower side of the baffle.

7. In a steam boiler having horizontally 125

inclined tubes divided into banks with a space therebetween, a baffle extending across the space and inclined to the vertical, said baffle comprising metallic plates extending from the lower to the upper bank and located side by side across the space, said plates having vertical bulbed projections on their front and lower faces and tile having recesses engaging said bulbed projections and suspended on the lower side of the baffle, said bulbed projections extending from the upper bank downward, and each bulb having a plurality of tile threaded thereon, the bulb terminating at a point above the lower bank a distance sufficient to permit the recess in each separate tile to be moved into alinement with the bulbed projections.

8. In a steam boiler having horizontally inclined tubes divided into banks with a space therebetween, a baffle extending across the space and inclined to the vertical, said baffle comprising metallic plates extending from the lower to the upper bank and located side by side across the space, said plates having projections on their front and lower faces, means to anchor said plates to prevent their overturning, and tile attached to the said projections and suspended on the lower faces of said plates, the joints between the sides of the plates being out of alinement with the joints between the sides of vertical rows of tile.

9. In a steam boiler having horizontally inclined tubes divided into banks with a space therebetween, a baffle extending across the space and inclined to the vertical, said baffle comprising metallic plates extending from the lower to the upper bank and located side by side across the space, said plates having vertical bulbed projections on their front and lower faces and tile having recesses engaging said bulbed projections and suspended on the lower side of the baffle, the recesses in the tile for the bulbed projections being formed partly in each face of adjacent tile and the joint between such adjacent side faces at the front of the tile being out of alinement with the recesses of the projections.

10. In a steam boiler having horizontally inclined tubes divided into banks with a space therebetween, a baffle extending across the space and into and across the upper bank, the lower portion of the baffle across the space being inclined to the vertical, said lower portion comprising metallic members extending across the space and tile attached to and at least partly supported by said metallic members, the upper part of the said lower portion being connected to the portion of the baffle extending across the upper bank to cause said upper portion to assist in resisting the overturning of the said lower portion of the baffle.

11. In a steam boiler having horizontally

inclined tubes divided into banks with a space therebetween, a baffle extending across the space and into and across the upper bank, the lower portion of the baffle across the space being inclined to the vertical, said lower portion comprising metallic members extending across the space and tile attached to and supported at least partly by said metallic members on the lower side of the baffle, the upper part of said metallic members being connected to the portion of the baffle extending across the upper bank to cause said upper portion to assist in resisting the overturning of the said lower portion of the baffle.

12. In a steam boiler having horizontally inclined tubes divided into banks with a space therebetween, a baffle extending across the space and into and across the upper bank, the lower portion of the baffle across the space being inclined to the vertical, the upper portion of the baffle in the upper bank comprising metallic plates anchored to the tubes and the said lower portion comprising metallic members extending across the space and connected at their upper portions to the metallic plates of the upper portion and tile attached to and at least partly supported by said metallic members on the lower side of the baffle.

13. In a steam boiler having horizontally inclined tubes divided into banks with a space therebetween, a baffle extending across the space and into and across the upper bank, the lower portion of the baffle across the space being inclined to the vertical, the upper portion of the baffle in the upper bank comprising metallic plates anchored to the tubes and the said lower portion comprising metallic plates extending from the lower bank to the upper bank across the space and positioned side by side across the boiler, the upper ends of the plates being connected to the metallic plates of the upper portion of the baffle and the plates of the lower portion of the baffle having vertical projecting ribs on the lower faces thereof, and tile having recesses engaging said ribs.

14. In an inclined baffle arranged between spaced banks of water tubes, supporting members provided with bulb projections, tiles provided with recesses engaging said bulb projections and exposed on their free faces to the furnace, the recess in the tiles for each bulb projection and the associated joint between adjacent tiles being so formed as to preclude a straight path being produced for the radiant heat to the bulb projections.

15. In a water tube boiler, spaced banks of water tubes, a superheater located between the said banks, an inclined baffle arranged between the spaced banks of water tubes, said baffle comprising supporting members provided with bulb projections, tiles provided with recesses engaging said bulb projections and exposed on their free faces to the furnace, the joints between adjacent tiles being suf-

ficiently deformed to preclude a straight path for the radiant heat being produced to said bulb projections.

16. In combination, supporting members having bulb projections, tiles provided on adjacent sides with recesses engaging said bulb projections, the rear portion of the joint between two adjacent tiles being located opposite the associated bulb projections and at right angles to the rear faces of the tiles, and the front portion of the joint at the front side of the tiles being at right angles to the front faces of the tiles and offset from said rear portion.

15 17. In combination, supporting members having bulb projections, tiles provided on adjacent sides with recesses engaging said bulb projections, the rear portion of the joint between two adjacent tiles being located opposite the associated bulb projection and at right angles to the rear faces of the tiles, and the front portion of the joint at the front side of the tiles being at right angles to the front faces of the tiles and offset from said 20 rear portion, the front and rear portions of the joint between two adjacent tiles being joined by an intermediate portion in which the change in direction is gradual.

18. In combination, supporting members 30 having bulb projections, tiles provided on adjacent sides with recesses engaging said bulb projections, the joint between two adjacent tiles comprising front and rear portions at right angles to the faces of the tiles, the rear 35 portion being opposite the associated bulb projection and the front portion offset from the rear portion, the front and rear portions of said joint being joined by an intermediate portion in which the change in direction 40 is gradual.

19. In combination, a wall comprising tiles laid edge to edge and forming joints therebetween, the rear portion of a joint between two given adjacent tiles forming substantially 45 a right angle with the rear faces of the tiles, and the front portion of the joint forming substantially a right angle with the front faces of the tiles and offset from said rear portion of the joint, the front and rear portions of the joint being joined by an intermediate portion in which the change in direction 50 is gradual, and a metallic member associated with said wall and located at the rear thereof and opposite said joint.

55 DAVID S. JACOBUS.
